1

My invention relates in general to radio frequency systems and more particularly to the control of radio transmitting system.

This invention constitutes an improvement upon the inventions shown and described in my patent, No. 2,395,049, issued February 19, 1946, for Radio signalling system and my patent, No. 2,415,427, issued February 11, 1947, for Radio frequency transmitter.

An object of my invention is to operate two or more amplifying tubes with an output resonant circuit, wherein the cathodes are the control elements for the high frequency system, or wherein other elements are coupled to the cathodes to give a combined action.

Another object of my invention is to obtain high efficiency with a minimum of distortion.

Another object is to amplitude modulate radio frequency with the control grids and shields as control elements for the low frequencies.

Another object is to neutralize the phase displacement of one tube by that of the other.

Another object is to render my invention highly efficient by reducing the modulation requirements.

Another object of my invention is to operate an amplifying tube in such a manner that an additive negative cycle exists on the cathode in addition to the constant radio frequency potentials applied to the cathode drive circuit.

Another object of my invention is to operate an amplifying tube in such a manner that a positive cycle or a portion of a positive cycle exists on the plate in addition to the constant potentials on the plate substantially concurrently with the existence of the said additive negative cycle on the cathode.

Another object of my invention is to operate the control grids or elements of an amplifying tube as valves, and avoid their carrying radio frequency energy.

Another object of my invention is to obviate the need for neutralizing a push-pull arrangement for radio frequency.

Other objects and a fuller understanding of my invention may be had by referring to the following description and claims, taken in conjunction with the accompanying drawing which comprises a single figure embodying the features of my invention.

The figure shows a schematic diagram of my circuit and may be characterized as a highly efficient amplitude modulated amplifier system. My invention comprises generally a carrier wave input resonant circuit indicated generally by the

2

reference characters 1, 2 and 4, and amplifying tube 6; a radio frequency output resonant circuit 14, 15, and 16, two push-pull modulated amplifying tubes 31 and 37, a modulation input transformer 26, and an output load circuit 47, 48, 49 and 50.

The carrier wave input circuit 1, 2 and 4 is coupled to the control grid 9 of the radio frequency amplifying tube 6 by a grid coupling condenser 3. The screen grid 8 is connected to the power supply 54 through a dropping resistance 12 and is by-passed to ground by the capacitor 11. The cathode 10 is connected to ground. The plate 7 is connected to the output resonant circuit 14, 15 and 16. A plate radio frequency choke 13 is connected between the power supply 51 and the plate 7 and prevents radio frequency from entering the power supply. The output resonant circuit 14, 15 and 16 may be characterized as a double-ended circuit, in that the center portion of the inductance 16 is maintained substantially at ground potential. Thus the energy delivered to the amplifying tube 31 through the coupling condenser 17 is substantially 180 degrees out of phase to the radio frequency energy delivered to the amplifying tube 37 through the coupling condenser 18.

In my invention I apply the radio frequency energy from the coupling condenser 17 to both the cathode 36 and the screen or accelerating grid 34 of the tube 31. Similarly the radio frequency from the coupling condenser 18 is supplied to both the cathode 42 and the screen or accelerating grid 40 of the tube 37. As illustrated, the screen or accelerating grid 34 of the tube 31 is connected to the cathode 36 through a high frequency coupling condenser 20 and the screen or accelerating grid 40 of the tube 37 is coupled to the cathode 42 through a high frequency coupling condenser 19. The coupling of the screen grid to the cathode is to prevent electron flow in the tube between the cathode and screen grid at radio frequencies which would normally tend to flow instantaneously to the cathode tending to swing away from the screen grid if the screen grid were maintained at a fixed potential. In other words, in my invention the screen grid swings with the cathode with the result that less radio frequency energy is required to efficiently drive the cathode circuit. This arrangement tends to reduce distortion. The cathodes 36 and 42 are connected to ground respectively through high frequency filter chokes 24 and 23 to prevent the radio frequency from flowing to ground, thus maintaining the cathodes at high

frequency potentials. Consequently the two tubes 31 and 37 are cathode driven and modulation is applied to the control grids 35 and 41 from the modulation input transformer 26, with the control grids by-passed to ground for radio frequency through the high frequency condenser 43. As shown, the amplifying tubes 31 and 37 are of the beam type and the beam-forming plates and associated shields, identified respectively by the reference characters 33 and 39, are also connected to the modulation input transformer 26. In this manner the beam-forming plates and associated shields are biased with the control grids and thus will not attract electrons that are emitted by the cathodes. This arrangement not only reduces the load on the cathode but also prevents distortion. The lower end of the secondary of the modulation input transformer 26, is connected to a bias source 55 and is maintained at a fixed potential through the low frequency by-pass condenser 46.

The terminals of the output resonant load circuit 47, 48 and 49 and 50 are coupled respectively to the plates 32 and 38 of the tubes 31 and 37 by coupling condensers 44 and 45. The load circuit may be tuned to resonance by operating the inductances 49 and 50 and the condensers 47 and 48. The resonant load arrangement is double-ended for push-pull operation.

The system so far described is completely operative for delivering output energy to the load with good linear modulation response. However in order to prevent saturation of the screen grids 34 and 40 at excessive modulation peaks, I arrange for feeding back inversely a small portion of the modulation energy from the plates 32 and 38 to the screen grids 34 and 40. This inverse feed-back arrangement comprises generally an inverse feed-back transformer 25 which has its primary connected to the plates 32 and 38 through high frequency chokes 30 and 29 respectively and which has its secondary connected to the screen grids 34 and 40 through high frequency filter chokes 21 and 22 respectively, thus delivering modulation energy to the screen grids.

The lower end of the primary of the inverse feed-back transformer 25 is connected to a power supply 56 and the lower end of the secondary is maintained at a fixed potential by the condenser 28. The resistor 27 is a current limiting resistance for the screen grids 34 and 40.

In operation stable radio frequency is applied to the terminals of the input inductance 1 and, in turn is impressed upon the control grid 9 which is connected to ground through a resistor 5, and which governs the operation of the high frequency amplifying tube 6. The amplified energy from the tube 6 is delivered to the double-ended output resonant circuit 14, 15 and 16, from which opposite phase energy is fed to the cathodes and the screen or accelerating grids of the two tubes 31 and 37 of the push-pull amplifier arrangement. Modulation is applied to both the control grids 35 and 41 and the beam-forming plates and accompanying shields 33 and 39. Under modulation, the two tubes 31 and 37 deliver modulated energy to the double-ended output resonant circuit 47, 48 and 49 and thereupon to the load across the terminals of the inductance 50. Under excessive conditions of modulation the inverse feed-back transformer arrangement is effective to reduce distortion which would tend to occur from overload.

With the tubes 31 and 37 operating in a push-

pull arrangement and with the cathodes and the screen grid driven by radio frequency energy and with the control grid and the beam-forming plates and the associated parts by-passed to ground for radio frequency, I am able to obtain a high efficient operating condition wherein the radio frequency drive voltage can be considered additive on the negative cycle to the constant radio frequency potentials applied to the cathode drive circuit. The additive negative cycle on the cathode of one tube is the operative cycle of the tube and the opposite cycle is the operative cycle of the other tube. This means that I am able to add the full radio frequency drive voltage to the constant radio frequency potentials applied to the cathode, thereby producing a greater peak modulation. During this cathode negative cycle, the grid will be positive and maximum electrons will be emitted from the emitting elements of the tubes. As the screen grid is also negative a minimum of electrons will be received by it. This arrangement is unique; in that, the input and output circuits of the tube, as well as the control elements may be arranged such that while the additive negative cycle on the cathode exists there concurrently exists an additive positive cycle upon the plate to the constant potential on the plate. The additive positive cycle may be substantially in alignment with the negative additive cycle on the cathode or they may be shifted with respect to each other, so that additive negative energy is existing on the cathode while additive positive energy exists upon the plates. In any event there may exist, at least a portion of or substantially all of the additive positive cycle with respect to the additive negative cycle to produce an effectively greater amplitude of voltage on the tube for modulation requirements.

In addition to having a highly efficient amplifier tube system I am able to obtain a good linear response because the grid and the beam-forming plate parts merely act as valves and do not carry any radio frequency energy. In my general push-pull arrangement, since the control grid and beam-forming plate parts are by-passed to ground for radio frequency, there is no need for neutralizing the circuit for radio frequencies.

Although I have shown and described my invention with a certain degree of particularity, it is understood that changes may be made therein without departing from the spirit of the invention which are included within the scope of claims hereinafter set forth.

I claim as my invention:

1. A radio frequency transmitting system comprising at least two amplifying tubes connected in a push-pull arrangement, each said tube having a cathode, a control element, an accelerating grid and a plate, a source of carrier wave potentials applied to the cathode of each amplifying tube with at least part of the plate-to-cathode carrier current of the amplifying tubes flowing through the source of carrier wave potentials, the control element of each amplifying tube being by-passed to ground for carrier wave frequency, the plate of each tube being connected to a resonant output load circuit, and means for applying modulating potentials to the control element of each amplifying tube, the accelerating grid of each amplifying tube being coupled to the cathode.

2. A radio frequency transmitting system comprising at least two amplifying tubes connected in a push-pull arrangement, each said tube hav-

ing a cathode, a control element, an accelerating grid and a plate, a source of carrier wave potentials applied to the cathode of each amplifying tube with at least part of the plate-to-cathode carrier current of the amplifying tubes flowing through the source of carrier wave potentials, the control element of each amplifying tube being by-passed to ground for carrier wave frequency, the plate of each tube being connected to a resonant output load circuit, and means for applying modulating potentials to the control element of each amplifying tube, the accelerating grid of each amplifying tube being coupled to the cathode, an inverse feed-back means for feeding a small portion of the modulated energy to the accelerating grids.

3. A radio frequency transmitting system comprising at least two amplifying tubes of the beam type connected in a push-pull arrangement, each said tube having a cathode, a control element, an accelerating grid, beam-forming parts, and a plate, a source of carrier wave potentials applied to the cathode of each amplifying tube with at least part of the plate-to-cathode carrier current of the amplifying tubes flowing through the source of carrier wave potentials, the control element of each amplifying tube being by-passed to ground for carrier wave frequency, the plate of each tube being connected to a resonant output load circuit, and means for applying modulating potentials to the control element of each amplifying tube, the accelerating grid of each amplifying tube being coupled to the cathode, said beam-forming parts being connected to the control element in each tube.

4. A radio frequency system comprising an amplifying tube having a cathode, a control element and a plate, a source of carrier wave potentials, said cathode being grounded through the source of carrier wave potentials, a source of modulating potentials applied to the control element, said amplifying tube having an accelerating grid coupled to the cathode, and inverse feed-back means for feeding a small portion of the modulated energy to the accelerating grid.

5. In a radio frequency system comprising a driven amplifying tube having a plate circuit including a cathode, a source of carrier wave potentials including a driving amplifying tube having a plate circuit including a plate, an impedance element common to both plate circuits, whereby the driven amplifying tube reflects a varying impedance in the plate circuit of the driving amplifying tube, said impedance element being connected between the cathode of the driven tube and ground and between the plate of the driving tube and ground, said driven tube having control means, and a source of modulating potentials applied to the control means.

6. A radio frequency system comprising at least two amplifying tubes connected in a push-pull arrangement, said tubes each including a cathode and a plate, a source of carrier wave potentials for exciting the cathode of each tube with respect to a point of reference potential, a load circuit connected to the plate of each tube, modulating means for modulating the carrier wave energy supplied to said load circuit, said tubes each having a control element, and means independent of the control element-plate capacitance of the tubes connected to the load circuit for feeding energy from the load circuit to the control element.

7. A radio frequency transmitting system comprising at least two amplifying tubes connected

in a push-pull arrangement, said tubes each having a cathode, a first control element, a second control element and a plate, a source of carrier wave potentials for exciting the cathode of each amplifying tube with respect to a point of reference potential, the first control element of each amplifying tube being by-passed to the said point of reference potential for carrier wave frequency, a resonant output load circuit connected to the plate of each tube, means for applying modulating potentials to the first control element of each tube, the second control element of each amplifying tube being coupled to the cathode, and inverse feedback means for feeding a portion of the modulated energy to the second control element.

8. A radio frequency transmitting system comprising at least two amplifying tubes connected in a push-pull arrangement, said tubes each having a cathode, a first control element, a second control element and a plate, a source of carrier wave potentials for exciting the cathode of each amplifying tube with respect to a point of reference potential, the first control element of each amplifying tube being by-passed to the said point of reference potential for carrier wave frequency, a resonant output load circuit connected to the plate of each tube, means for applying modulating potentials to the first control element of each tube, the second control element of each amplifying tube being coupled to the cathode, and means receiving energy from the plate for feeding a portion of the modulated energy to the second control element.

9. A radio frequency system comprising an impedance element, a space discharge tube including an electron discharge path, a resonant load circuit, means to effectively connect in series said impedance element, electron discharge path, and resonant load circuit, means to supply carrier wave energy across the impedance element, modulating means for modulating the carrier wave output of said tube, said space discharge tube having a cathode and a control element, said cathode being grounded through said carrier wave supply means, and means connected to the load circuit for feeding energy from the load to the control element.

10. A radio frequency system comprising a space discharge tube including an electron discharge path, said tube having a cathode and output electrode means, a load circuit connected to the output electrode means, means to supply carrier wave energy to said cathode, said cathode being grounded through said carrier wave supply means, said tube having a first control electrode, means for applying modulating potentials to said first control electrode and thereby controlling said tube for supplying modulated energy to the load circuit, said tube having a second control electrode, and means connected to the load circuit for feeding modulated energy to said second control electrode.

11. A radio frequency system comprising an amplifying tube having a cathode, a first control element and a plate, a source of carrier wave potentials for exciting the cathode with respect to a point of reference potential, said cathode being grounded through said source of carrier wave potentials, means for applying modulating potentials to the first control element, said amplifying tube having a second control element coupled to the cathode, and means receiving energy from the plate for feeding a portion of the modulated energy to the second control element.

12. A radio frequency system comprising an amplifying tube having a cathode, a first control element and a plate, a source of carrier wave potentials for exciting the cathode with respect to a point of reference potential, said cathode being grounded through said source of carrier wave potentials, means for applying modulating potentials to the first control element, said amplifying tube having a second control element, and inverse feedback means for applying energy from said plate to said second control element.

13. A radio frequency system comprising at least two amplifying tubes connected in a push-pull arrangement, said tubes each having output electrode means, a load circuit connected to the output electrode means of each tube, high frequency choke means connected across said load circuit, said choke means having a center-tap, a transformer connected between said center-tap and a point of reference potential to receive energy from said load circuit, said amplifying tubes each having control means, and connection means for connecting the transformer to the control means of each tube for energizing the said control means.

14. In a radio frequency system comprising a driven amplifying tube having a plate circuit including a cathode, a source of carrier wave potentials including a driving amplifying tube having a plate circuit including a plate, an impedance element common to both plate circuits, whereby the driven amplifying tube reflects a varying impedance in the plate circuit of the driving amplifying tube, said impedance element being connected between the cathode of the driven tube and ground and between the plate of the driving tube and ground, said driven tube having control means, a source of modulating potentials applied to the control means, and inverse feedback means for feeding a portion of the modulated energy to the control means.

15. In a radio frequency system comprising a driven amplifying tube having a plate circuit including a cathode, a source of carrier wave potentials including a driving amplifying tube having a plate circuit including a plate, an impedance element common to both plate circuits, whereby the driven amplifying tube reflects a varying impedance in the plate circuit of the driving amplifying tube, said impedance element being connected between the cathode of the driven tube and ground and between the plate

of the driving tube and ground, said driven tube having first and second control means, a source of modulating potentials applied to the first control means, and inverse feedback means for feeding a portion of the modulated energy to the second control means.

16. A radio frequency system comprising at least two amplifying tubes connected in a push-pull arrangement, said tubes each having output electrode means, a load circuit connected to the output electrode means of each tube, high frequency choke means connected across said load circuit, said choke means having a center-tap, a transformer connected between said center-tap and a point of reference potential to receive energy from said load circuit, said amplifying tubes each having first and second control means, a source of modulating potentials applied to the first control means, and connection means for connecting the transformer to the second control means of each tube for energizing the said second control means.

17. A radio frequency system comprising an impedance element, a space discharge tube including an electron discharge path, a resonant load circuit, means to effectively connect in series said impedance element, electron discharge path, and resonant load circuit, means to supply carrier wave energy across the impedance element, said space discharge tube having a cathode and a control element, condenser means connected between said cathode and said control element, and means connected to the load circuit for feeding energy from the load to the control element.
